UNITED STATES PATENT OFFICE.

FREDERICK W. NURENBERG, OF NEW YORK, N. Y., ASSIGNOR TO THE
FAIRBANKS COMPANY, OF SAME PLACE.

DESIGN FOR A FRAME FOR COPYING-PRESSES OR SIMILAR ARTICLES.

SPECIFICATION forming part of Design No. 34,033, dated February 5, 1901.

Application filed January 10, 1901. Serial No. 42,811. Term of patent 14 years.

To all whom it may concern:

Be it known that I, FREDERICK W. NURENBERG, a citizen of the United States, residing at the city of New York, (Brooklyn,) county of Kings, and State of New York, have invented and produced a new and original Design for Frames for Copying-PresSES and Similar Articles, of which the following is a specification.

10 In the drawings forming part of this specification, Figure 1 is a plan view of the frame. Fig. 2 is a side elevation; Fig. 3, a plan sectional elevation on the line 3 3, Fig. 2; and Fig. 4 is a sectional elevation on the line 4 4, Fig. 2.

As shown in the drawings, the leading or material features of my design are as follows, viz: The two vertical posts or pillars 1, which are duplicates of each other, and when regarded independently of the arch 2, by which they are united, they are of uniform size and shape from top to bottom, except at the point 20 3, where they curve over and merge into the arch, and relatively to each other are uniformly of the cross-section shown in dotted

lines in Fig. 1, where the bead 4 is shown extending inwardly from their flattened inner faces, the arch 2, into which the posts merge, being flat and horizontally expanded into a ledge 5, which extends over and beyond the main web of the arch, as shown in Figs. 1 and 3. At the center the web of the arch is flared out to form the pendent lug 6, the sides of which converge downwardly, and the bead 4 merges into the lug by a gradual expansion 35 of the material, as indicated in dotted lines in Fig. 1.

The design consists, essentially, in the appearance of the article as it is derived from the shape of the posts and arch. 40

I claim—

The design for a frame for a copying-press, or similar article, substantially as herein shown and described.

Signed at the city, county, and State of New York this 7th day of December, 1900.

F. W. NURENBERG.
